am Main, Germany

Filed Mar. 1, 1962, Ser. No. 176,693
6 Claims. (Cl. 317—139)

The present invention relates to a fire circuit arrangement for use in electrically actuated firearms.

For the firing of automatic firearms, which are normally set for sustained fire, it is necessary to provide a magnetic drive which renders it possible to fire single rounds with this equipment. By means of this magnet, for instance a firing linkage may be actuated which is restored to the initial position by a spring after the magnet has been switched off.

A known switching device working in this manner is illustrated diagrammatically in FIGURE 1 of the drawing.

In this switching device, *a* is an actuating switch, *d* is a selector switch for switching on continuous fire or individual rounds selectively, and *g* is the magnet. Reference character *e* is an auxiliary switch coupled to the magnet, *c* is an operating relay with its switch *c*₁, and *b* is an auxiliary relay with the normally closed main switch *b*₁, and the self-holding switch *b*₂. The letters *k*, *l*, *m* designate interference suppression members.

The selector switch *d* provides continuous fire in its open position. If the actuating switch *a* is operated, the relay *c* closes its switch *C*₁ in the operating circuit. The magnet *g* remains energized until the switch *a* is opened again. The switches of the relay *b* remain in the normal position because no voltage is applied to the relay coil.

For single rounds, the selector switch *d* is closed. As a result of operation of the actuating switch *a*, the coil of the relay *c* is connected across the voltage source and the switch *c*₁ closes the operating circuit so that the magnet *g* is energized and thus operates the fixing linkage. As a result, the auxiliary switch *e* coupled to the magnet is closed so that the coil of the relay *b* also is connected across the voltage source. The operation of this relay causes an interruption of the operating circuit through the switch *b*₁ and hence immediate release of the magnet. Since the relay *b* is self-holding via the switch *b*₂, this interruption in the operating circuit through the switch *b*₁ lasts until the control voltage is switched off through the opening of the actuation switch *a*, and the switch *b*₁ in the operating circuit is closed by the release of the relay *b*. On the opening of the actuating switch *a*, the relay *c* is also de-energized, and this in turn maintains the interruption of the operating circuit as a result of the opening of the switch *c*₁. Thus, a further individual round is only fired as a result of a fresh instruction through the switch *a* i.e., each actuation of switch *a* produces but one short actuation of the operating relay, and consequently of the magnet.

This switching device has the disadvantage that the switch of two relays *b* and *c* lie in the operating circuit and that these switches *b*₁ and *c*₁ have to be designed for the operating power of the magnet, and an additional switch *b*₂ for lower operating power is needed for the relay *b*. In addition, each switch in the operating circuit requires an additional interference elimination which is designated by *k* and *l* in FIGURE 1.

It is, therefore, an object of the present invention to provide a fire circuit arrangement which overcomes the above drawbacks, and, with this object in view, the present invention resides in a firing circuit arrangement whose operating circuit includes but a single control switch.

2

Additional objects and advantages of the present invention will become apparent upon consideration of the following description when taken in conjunction with the accompanying drawings in which:

5 FIGURE 1 is, as described above, a circuit diagram representative of the prior art.

FIGURE 2 is a circuit diagram of a fire circuit arrangement according to the present invention.

The switching device according to the invention, which 10 is shown in FIGURE 2, avoids the relatively high expenditure of switches and interference suppression members in the operating circuit without significantly increasing the expenditure required for the control circuit. Reference character *a* is the actuator switch, *r* the selector switch 15 for selectively switching on continuous fire or single rounds, and *g* is the magnet connected to the firing linkage, shown schematically. The auxiliary switch coupled to the magnet is designated by *p*. The operating relay is designated by the letter *t* and its switch *t*₁ is the single control switch of the operating circuit. The unenergized auxiliary relay *s* has the normally closed main switch *s*₁ and the normally opened holding switch *s*₂. The reference characters *o* and *m* represent the suppression members.

The mode of operation is as follows: During continuous 20 fire, the selector switch *r* is closed. If then the switch *a* is actuated, the relay *t* is connected across the voltage of the current source means via switch *r* and thus becomes energized. As a result, the control switch *t*₁ in the operating circuit is closed and the magnet is energized. At 25 the same time, the auxiliary switch *p*, which includes the three terminals 1, 2, 3, and, through its mechanical coupling with the magnet of the operating circuit, establishes an electrical connection between terminals 1 and 3 when the magnet is not energized and between terminals 2 and 35 3 when the magnet is energized, is moved to its last-named position so that the relay *s* has a voltage applied to it and remains self-holding via switch *s*₂ so long as the actuator switch remains closed. As a result of opening *a*, the relays *t* and *s* are de-energized so that the magnet 40 releases and the continuous fire is terminated.

For single rounds, the selector switch *r* is opened. As a 45 result of actuating the switch *a*, the operating relay *t* has voltage applied across it via the auxiliary switch *p* coupled to the magnet and via switch *s*₁, so that the magnet is energized and at the same time brings the auxiliary switch *p* coupled thereto into the position where it establishes the electrical connection between terminals 2 and 3. As a result of this changeover, the coil of the 50 relay *t* is de-energized and at the same time the auxiliary relay *s* now has the voltage applied to it and becomes self-holding by the means of its holding switch *s*₂. Since the relay *t* has become deenergized, the operating circuit is interrupted again as a result of the opening of *t*₁ and the magnet is restored to its normal position. Since the auxiliary relay *s* is still energized, the switch *s*₁ is open 55 and the operating relay *t* cannot operate again, even when the switch *p* has returned to the position 1, 3, until the auxiliary relay *s* becomes de-energized as a result of opening of the switch *a* and the contact *s*₁ closes again. Only then can another single round be fired.

The circuit according to the invention has, in particular, the advantage that only a single relay is required to control the operating circuit. This is useful because relay switches in the operating circuit have to be designed 65 for the operating power of the magnet. To this must be added the fact that, as a result of the reduction in the number of switches, the susceptibility to faults and necessary maintenance of the installation are less. Moreover, as a result of the absence of further switches in the operating circuit, the cost of suppression members is reduced. This is particularly important when the installation has

to be shielded for radio interference. The auxiliary relay s can be dimensioned for comparatively small power because its switches s_1 and s_2 are used for low control currents only.

What is claimed is:

1. A fire circuit arrangement comprising, in combination:

- (1) an operating circuit incorporating
  - (a) an operating magnet, and
  - (b) a single control switch electrically connected to said magnet for energizing the same; and
- (2) a control circuit incorporating
  - (a) an operating relay mechanically connected to said control switch,
  - (b) an actuator switch, and
  - (c) switch means interconnecting said operating relay and said actuator switch for switching said control circuit between a first position in which said operating relay, and consequently said magnet, remain continuously actuated so long as said actuator switch is actuated, and a second position in which each actuation of said actuator switch produces but one short actuation of said operating relay, and consequently of said magnet.

2. A fire circuit arrangement as defined in claim 1 wherein said switch means comprise a selector switch and an auxiliary switch mechanically connected to said magnet to be opened thereby when said magnet is de-energized, said auxiliary switch being connected in series-circuit with said operating relay in consequence of which said auxiliary switch, when said switch means is switched into its second position by said selector switch, interrupts said series-circuit.

3. A fire circuit arrangement comprising, in combination:

- (1) an operating circuit incorporating
  - (a) an operating circuit current source means,
  - (b) an operating magnet, and
  - (c) a single control switch electrically connected to said magnet and said operating circuit current source means for energizing the former when said control switch is closed; and
- (2) a control circuit incorporating
  - (a) a control circuit current source means;
  - (b) an operating relay mechanically connected to said control switch such that the latter is closed when said operating relay is energized,
  - (c) an auxiliary relay having, and being mechanically connected to, main and holding switches, said main switch being open and said holding switch being closed when said auxiliary relay is energized,

(d) an auxiliary switch mechanically connected to said magnet and having first, second and third terminals, said auxiliary switch establishing an electrical connection between said first and third terminals when said magnet is not energized and between said second and third terminals when said magnet is energized.

(e) a selector switch, and

(f) an actuator switch,

(i) said operating relay, said main switch of said auxiliary relay, so much of said auxiliary switch which includes said first and third terminals thereof, and said actuator switch forming a series circuit which is connected across said control circuit current source means,

(ii) said selector switch being connected across a first portion of said series circuit which includes said first switch of said auxiliary relay and said first and third contacts of said auxiliary switch,

(iii) said auxiliary relay and said holding switch thereof forming another series circuit which is connected across a second portion of said first-mentioned series circuit which includes said first portion thereof as well as said operating relay, and

(iv) so much of said auxiliary switch which includes said second and third terminals thereof being connected across said holding switch of said auxiliary relay.

4. A first circuit arrangement as defined in claim 2 wherein said switch means further comprise auxiliary relay means effective when said switch means is in its second position and energizable by said auxiliary switch when said magnet is energized for preventing a renewed actuation of said control switch unless said actuating switch is again actuated.

5. In combination with a firing circuit arrangement as defined in claim 1, a firing linkage connected to said operating magnet to be actuated thereby.

6. In combination with a firing circuit arrangement as defined in claim 3, a firing linkage connected to said operating magnet to be actuated thereby.
